GARMENT RETAINING MEANS

Peter H. Simonsen, Avon, N. J.

Application February 1, 1950, Serial No. 141,629

8 Claims. (Cl. 223—88)

1

This invention relates to improvements in means for retaining and supporting garments in smoothly folded condition, especially when packed into luggage for transportation.

In modern wardrobe trunks, and in suitcases having capacity for carrying one or more men's suits, provision is usually made for suspending or otherwise supporting the garments in a folded condition when packed. Devices as heretofore provided for such purpose, while intended to maintain the garments in smoothly folded condition free from wrinkles, have not successfully avoided all wrinkling, especially with respect to coat sleeves in the vicinity of the junctures thereof with the shoulders of the coat. When a coat is folded for packing in luggage, the sleeves are flattened and inwardly swung or inclined to lay over the front of the coat. When the sleeves are thus inswung and overlaid across the coat front, considerable undesirable puckering and wrinkling of the unsupported material of the sleeves occurs with respect to the sleeve portions which extend adjacently below the shoulder seams. Under these conditions, when the coat is packed and tightly compressed within the luggage interior, the aforesaid wrinkles become creased so as to remain in the coat after it is unpacked, to the detriment of the coat appearance when again worn.

Having the above in view, it is an object of this invention to provide a device for retaining garments, especially when packed into luggage, in smoothly folded condition and with the sleeves thereof so supported by novel fold guiding and shielding means, that puckering and wrinkling or sharp creasing of the folded sleeve material adjacent the shoulders of the garments is effectively prevented.

The invention has for a further object to provide a garment retaining device having novel sleeve fold guiding and shielding means, including means to adjustably support the latter whereby to accommodate the same to different sizes of garments.

Other objects of this invention, not at this time more particularly enumerated, will be understood from the following detailed description of the invention.

Illustrative embodiments of the invention are shown in the accompanying drawings, in which:

Fig. 1 is a front face view of the novel garment retaining device of this invention, in a hanger form thereof suitable for use in wardrobe trunks, and showing its operative application to a coat, the latter being delineated by broken lines; Figs.

2 and 3 are fragmentary horizontal sectional views, taken on line 3—3 in Fig. 1; Fig. 2 showing a sleeve fold guiding and shielding means as initially up-swung for introduction into a sleeve interior; and Fig. 3 showing said fold guiding and shielding means down-swung to fold forming and supporting relation to the sleeve material; and Fig. 4 is a transverse vertical sectional view, taken on line 4—4 in Fig. 2, but drawn on an enlarged scale.

Fig. 5 is a front face view of a modified form of the garment retaining device of this invention which is adapted for use in suitcases, this view also showing operative application of the device to a coat, the latter being delineated by broken lines; and Fig. 6 is a detail transverse vertical sectional view, taken on line 6—6 in Fig. 5, but drawn on an enlarged scale.

Similar characters of reference are employed in the hereinabove described views to indicate corresponding parts.

Referring first to Figs. 1 to 4 inclusive of the drawings, the novel garment retaining device is shown as of a coat-hanger type, and comprises a suitably formed and shaped substantially flat hanger frame 10, which is provided at its upper midportion with a suspension means 11. Said suspension means is preferably pivotally supported so as to be reversible, one end thereof comprising a hook-loop 12 suitable for engagement with a suspension bar (not shown) in a closet, and the opposite end thereof comprising a hook formation 13 suitable for engagement with a suspension bracket or like device (not shown) of a wardrobe trunk. The hanger frame terminates at its respective outer ends in dependent side members 14, and extending between these side members 14 is a horizontal transverse bar 15 over which folded trousers may be disposed for suspension therefrom. Supported from and below the mid-portion of said transverse bar 15 are the inner ends of oppositely extending trackway members 16, the opposite outer ends of which are affixed to and are supported by the side members 14.

The coat-hanger type of the garment retaining device, with respect to the above described parts thereof, may be made of any suitable material, and may be variously constructed as to the detail structure thereof. For purposes of illustration, and to exemplify one structural form thereof, the hanger frame 10 and its side members 14, the transverse bar 15, and the trackway members 16 are fabricated from substantially rigid metallic wire or like material. In such case,

the trackway members 16 each comprises parallelly spaced apart track bars 17, the inner ends of which are supported from the transverse bar 15 by a suspension element 18 which depends from the latter; the outer ends of the track bars 17 being affixed to and supported by the hanger frame side members 14.

In the coat-hanger type of the garment retaining means of this invention, the trackway members 16 are disposed to incline downwardly and outwardly from their inner ends to their outer ends; the purpose of which arrangement will be hereinafter more fully explained.

Mounted in connection with the respective trackway members 16, so as to be longitudinally adjustable therealong, are respective sleeve fold guiding and shielding devices 20, whereby one of the latter is provided at each side or end of the garment retaining means.

Means is provided for supporting each sleeve fold guiding and shielding device, the same comprising a carrier member 21 which is slidably movable on a trackway member 16; means being provided for releasably holding the carrier member in desired adjusted position on the trackway member. To the lower part of the carrier member 21 is fixed a longitudinally and outwardly extending bracket arm 22 which terminates at its outer end in an outwardly projecting angular extension 23, from which extension depends a pintle arm 24. The sleeve fold guiding and shielding device is pivotally supported by said pintle arm 24, and for this purpose is provided with a hinging member 25 disposed to project from the back or inner face thereof at a suitable location adjacent to its outer side margin. This hinging arrangement is such that the sleeve fold guiding and shielding device may be outswung from a closed position, substantially parallel to and spaced from the plane of the garment retaining means, to an open position, substantially at right angles to such plane. Said respective positions are determined by stop shoulder formations 26 and 27, with which the upper end portion of the hinge member 25 is provided, and which are adapted to be selectively brought into stopped abutment against the angular extension 23 of the bracket arm 22. It is especially important that stop shoulder formation 26 shall prevent body 20 from approaching too close to frame members 14 and 16, for a purpose which will appear presently.

In one illustrative form thereof, as shown in Figs. 1 to 4 inclusive, the carrier member 21 comprises a plate 28 having longitudinal top and bottom marginal portions or shoulders 29 which are adapted to embrace the spaced track bars 17, and cooperative with said plate 28 is a clamping bridge piece 30 and a clamp screw 31 which extends therefrom between the track bars 17 so as to screw into the plate 28. When the clamp screw is tightened, the bridge piece 30 and plate 28 are drawn together into gripping relation to the track bars 17, whereby to hold the carrier member 21, and sleeve fold guiding and shielding device carried thereby, in a selected position to which it may have been shifted along the trackway member.

The sleeve fold guiding and shielding devices 20 each comprise a substantially flat molded or otherwise shaped body which may be optionally made of hard and rigid material, such as wood, hard plastic or the like, or of relatively soft and resilient material, such as natural or synthetic rubber or the like. The peripheral shape of the

body is preferably such as to provide a curvilinear outer margin 40 and a substantially straight inner margin 41 bordered by a lip 42 of rounded cross-section. In such form, the substantially straight inner margin 41 provides a sleeve fold guide and the lip 42 a fold distending support, all as will presently be explained. It is also preferable that the body of the device 20 be of substantially concavo convex formation, with the concave side at its inner face, whereby to add to the shielding effect of the space between said body and members 14 and 16 of frame 10 to provide housing reception of slack sleeve material when the latter is folded about the body 20.

In the use of the coat-hanger type of the garment retaining means of this invention, a coat is draped over the hanger frame 10, so that the latter supports the shoulders of the garment in the usual manner. After the coat is thus disposed, the sleeve fold guiding and shielding devices 20 are out-swung to open position, and when so positioned are inserted through the arm holes of the garment and respectively into the sleeve interiors so as to be arranged therein adjacent to the junctures of the sleeves with the garment shoulders (see Fig. 2). The sleeve material is now smoothly folded around the lips 42 of the straight margins 41 of the devices, so that the inner portions of the folds are arranged contiguous to the concave inner faces of said devices, whereupon said devices are in-swung to overlie the front of the coat (see Fig. 3). In this manner, those portions of the respective sleeves which are disposed in the vicinity of the junctures thereof with the coat shoulders are neatly and smoothly folded about the devices 20, so as to be supported and shielded thereby, and retained in such folded condition free from puckles and wrinkles. As thus supported by the coat-hanger type of the garment retaining means, the garment may be suspended within a wardrobe trunk or like luggage piece, and then subjected to pressure of adjacent packed garments without risk of formation of undesired creased wrinkles therein.

As shown in Fig. 1, and as above described, the trackway members 16 are inclined downwardly and outwardly from their inner ends thus ascending toward said inner ends. The purpose of this arrangement is to permit adjustment of the relative spacing of the sleeve fold guiding and shielding devices 20, whereby to accommodate the same to different sizes of garments. In coats of small size, the shoulder breadth is narrower and the skirt length proportionately shorter than in coats of larger sizes. Consequently, for smaller sizes of coats the devices 20 are moved inwardly along the inclined trackway members 16, and due to the upward inclination of the latter, said devices 20 are likewise moved upward relative to the hanger frame 10, thus not only accommodating the devices 20 to the narrower spaced relation of the coat sleeves, but also to the proportionally shorter skirt length of the coat.

Referring now to Fig. 5, a modified form of the garment retaining means of this invention is shown therein, which form is suitable for use with garments desired to be packed into luggage pieces of the suitcase type which contain hanger bar or like means 50 over which the folded garment is disposed so as to depend therefrom. This type of garment retaining means comprises a transverse frame member 51 suitably formed to provide oppositely and outwardly extending trackway members 16. Said transverse frame mem-

ber and trackway members preferably comprise a channel bar formation, the upper flange of which, at least with respect to each trackway member part thereof, is provided along its free edge with dependent ratchet teeth 52. Slidable on the respective trackway members 16 are carrier members 21, preferably in the form of end-wise open sleeves 53 which embrace the trackway members. To the lower part of the sleeves 53 are fixed longitudinally and outwardly extending bracket arms 22 on the pintle arms 24 of which are pivotally mounted the sleeve fold guiding and shielding devices 20, in the same manner and so as to function in the same way as above set forth in connection with the first described form of the garment retaining means. Supported by anchor lugs 54 within the sleeves 53 comprising the carrier members 21 are spring pawls 55 which cooperate with the ratchet teeth 52, whereby to hold said carrier members, and the sleeve fold guiding and shielding means, in selected adjusted positions to which the carrier members may have been shifted along the trackway members 16. The spring pawls 55 are provided with finger pieces 56 projecting exteriorly of the sleeve 53, by means of which said spring pawls 55 may be depressed and disengaged from the ratchet teeth 52, when it is desired to move the carrier members 21 inwardly along the trackway members.

In the use of the last described form of the garment retaining means, the sleeve fold guiding and shielding devices 20 are inserted through the sleeve arm holes of a coat to be served, and then manipulated in the same manner as already above described, whereby to form and retain the sleeve folds. After the garment retaining means is thus applied to the coat, the latter may be folded upon itself over and so as to depend from a hanger bar 50 within the suitcase into which the coat is to be packed, as indicated in Fig. 5.

It may be here stated that form of trackway members and cooperative carrier members shown as to the suitcase type of garment retaining means may be utilized in the coat-hanger type of garment retaining means, and vice versa.

Having now described my invention, I claim:

1. A garment retaining means comprising a substantially flat frame member for insertion in a garment, sleeve fold guiding and shielding devices of substantially flat body formation respectively carried by the frame member at opposite end portions thereof, said devices and the frame member end portions by which they are carried having cooperative hinge elements operative to pivotally connect the former to the latter so that said devices are capable of being outswung for disposition angular to the frame member end portions subject to insertion into upper interiors of the respective garment sleeves and thereafter to be in-swung parallel to the plane of said frame member, and said hinge elements having cooperative stop means for limiting in-swinging movement of said devices to outwardly offset parallel disposition relative to the frame member, and thus to maintain sleeve fold shielding space between said devices and frame members.

2. A garment retaining means comprising a substantially flat frame member for insertion in a garment, said frame member having oppositely and outwardly extending trackway members, carrier members slidably adjustable on said trackway members, sleeve fold guiding and shielding devices of substantially flat body formation respectively carried by the carrier mem-

bers, said devices and the carrier members by which they are carried having cooperative hinge elements operative to pivotally connect the former to the latter so that said devices are capable of being out-swung for disposition angular to the plane of the frame member subject to insertion into upper interiors of the respective garment sleeves and thereafter to be in-swung parallel to the plane of the frame member, said hinge elements having cooperative stop means for limiting in-swinging movement of said devices to outwardly offset parallel disposition relative to the frame member, and thus to maintain sleeve fold shielding space between said devices and the frame member, and releasable means for holding the carrier members with the sleeve fold guiding and shielding devices in selected adjusted positions on the trackway members.

3. A garment retaining means comprising a substantially flat hanger-frame from which garments can be suspended, trackway members oppositely extending from a mid-portion of the hanger-frame at the bottom thereof to the opposite outer ends thereof, carrier members slidably adjustable on the trackway members, sleeve fold guiding and shielding devices of substantially flat body formation respectively carried by the carrier members, said devices and the carrier members by which they are carried having cooperative hinge elements operative to pivotally connect the former to the latter so that said devices are capable of being out-swung for disposition angular to the plane of the hanger-frame subject to insertion into upper interiors of the respective garment sleeves and thereafter to be in-swung parallel to the plane of the hanger-frame, said hinge elements having cooperative stop means for limiting in-swinging movement of said devices to outwardly offset parallel disposition relative to the hanger-frame, and thus to maintain sleeve fold shielding space between said devices and the hanger-frame, and releasable means for holding the carrier members with the sleeve fold guiding and shielding devices in selected adjusted positions on the trackway members.

4. A garment retaining means comprising a substantially flat hanger-frame from which garments can be suspended, trackway members oppositely extending from a mid-portion of the hanger-frame at the bottom thereof to the opposite outer ends thereof, carrier members slidably adjustable on the trackway members, sleeve fold guiding and shielding devices of substantially flat body formation respectively carried by the carrier members, said devices and the carrier members by which they are carried having cooperative hinge elements operative to pivotally connect the former to the latter so that said devices are capable of being out-swung for disposition angular to the plane of the hanger-frame subject to insertion into upper interiors of the respective garment sleeves and thereafter to be in-swung parallel to the plane of the hanger-frame, said hinge elements having cooperative stop means for limiting in-swinging movement of said devices to outwardly offset parallel disposition relative to the hanger-frame, and thus to maintain sleeve fold shielding space between said devices and the hanger-frame, and releasable means for holding the carrier members with the sleeve fold guiding and shielding devices in selected adjusted positions on the trackway members, said trackway members and the carrier members supported thereby being disposed in

downwardly and outwardly inclined extension from the hanger-frame mid-portion toward the opposite ends of said hanger-frame.

5. A garment retaining means as defined in claim 1, wherein the body of each sleeve fold guiding and shielding device has a concave inner face adapted to house and shield the slack sleeve material disposed between said device and the frame member when said device is in in-swung position.

6. A garment retaining means as defined in claim 1, wherein the body of each sleeve fold guiding and shielding device is concavo-convex in form and arranged to provide a convex sleeve distending outer face and a concave sleeve-slack 15 housing inner face.

7. A garment retaining means as defined in claim 1, wherein the body of each sleeve fold

guiding and shielding device has a substantially straight free fold guide edge opposite to its pivotal axis.

8. A garment retaining means as defined in claim 1, wherein the fold guide edge of each body of the fold guiding and shielding device has a lip of rounded cross-section to provide a fold distending support.
